CLAIM

The ornamental design for a wireless meat thermometer smart base, as shown and described.

DESCRIPTION

FIG. 1 is a front perspective view of a wireless meat thermometer smart base, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view in a use state 1 thereof; and, FIG. 10 is a perspective view in a use state 2 thereof.

The broken lines in the drawings illustrate the portions of the wireless meat thermometer smart base, which form no part of the claimed design.
